UNITED STATES PATENT OFFICE

HORACE D. MUNDAY, OF SCHENECTADY, NEW YORK

BRUSH HOLDER

Application filed May 18, 1928, Serial No. 278,752. Renewed May 9, 1931.

This invention relates to current collectors and particularly to brush holders adapted for use with commutators or slip rings.

One object of my invention is to provide a brush holder adapted for use with an abrasive member or with an abrasive brush, wherein the parts are so arranged as to cause the member or brush to exert a truing effect on the commutator of the machine with which it is used.

A further object of the invention is to provide an improved brush holder adapted for use with an abrasive member or an abrasive brush and which will cause the member or brush to exert a truing effect on the commutator of the machine with which it is used. A further object of my invention is to provide a brush holder with means for advancing or feeding the brush toward the commutator and preventing or resisting any backward motion of the brush. A further object of the invention is to provide a brush holder adapted for use on a machine which is subject to heavy vibration and wherein the wear on the moving parts of the brush holder is reduced to a minimum. A further object of my invention is to lessen the rebound of brushes on high speed electric machines, which rebound is apt to occur when slight irregularities exist in the commutator surface.

Sooner or later, from one cause or another, flat spots develop in many commutators and slip rings. An abrasive cloth and abrasive stones applied by hand are the expedients that are generally tried first to keep the machines in proper working condition. This treatment is generally unsatisfactory and the commutator continues to get worse until finally the machine has to be shut down and the commutator trued by other methods. Small armatures are generally taken out of their frames and the commutator trued in a lathe. The commutators of large machines are sometimes trued in place by a portable grinding or turning device. This operation is apt to consume several days during which the machine is out of commission. Undercutting of the mica in the commutator is one remedy tried for these obvious disadvantages.

On small commutators undercutting of the mica is not satisfactory because the slots formed in the commutator by the undercutting are apt to fill up with dirt and burn out the armature.

In employing the devices constructed in accordance with the present invention, I overcome the disadvantages just noted. The operation of such devices is automatic and does not require the constant attention of the operator. Furthermore it does not or need not interfere with the normal operation of the machine.

The abrasive or active member employed for truing the commutator may be a block formed of pure abrasive and adapted to be employed in a brush holder of the machine or otherwise associated with a brush holder, or the active member may contain conducting material in addition to abrasive material, and such member may function not only as the active truing element but also as one of the brushes of the machine.

In the preferred embodiments of my invention, means is provided for advancing the abrasive or active member toward the commutator and also for hindering the motion of the abrasive, that is, retarding or preventing motion of the abrasive toward or away from the commutator.

One effect of a hindering means employed by me is to prevent the abrasive from advancing quickly into a low spot of the commutator as the low spot passes under the abrasive and to confine the rubbing of the abrasive to the high spots of the commutator. Or in case the abrasive does enter the low spot of the commutator the hindering means will offer a high resistance to the backward or retrograde motion of the abrasive as the abrasive is being pushed back by the commutator surface onto the high spot. In either of these cases the abrasive will be pressed less against or toward the low spots of the commutator than against other portions of the commutator surface, with the result that ultimately the commutator will be ground to a true cylindrical surface.

The hindering means which I employ may be frictional or it may consist of a viscous

substance such as asphalt interposed between a stationary and movable part of the apparatus. Also, optionally, a sluggishly yielding metal such as lead or solder, may be employed. In certain cases, to provide a hindering of the backward or retrograde movement of the abrasive I may make use of the high resistance offered by a comparatively rigid grinding apparatus when the apparatus is caused to yield structurally a slight amount by the forcing backward of the abrasive by the high spot of the commutator. The weight of the grinding apparatus may contribute materially to this effect and if desired the apparatus may be weighted to increase its inertia.

The means of hindering the motion of the abrasive forms an important feature of the invention, together with the fact that the force for moving the abrasive is such that the advancement of the abrasive, radially at least, is harmlessly haltable on contact with the commutator.

With a viscous substance interposed to hinder the advancement of the abrasive towards the commutator, permitting the abrasive to move forward only slowly towards the commutator, the abrasive will slowly advance till it strikes the high parts of the revolving commutator. Since the speed of the commutator is so great in comparison with the slow speed of the abrasive that the abrasive is not able to feed forward into the low spots of the commutator while the commutator is making one revolution, it is evident that the low spots of the commutator will not be touched till all the high spots have been worn down. Consequently the commutator must necessarily become true.

In the use of friction hindering means for truing up a commutator there is the difference that in the case of friction both the high part and the low part of the commutator are worn down at the same time—the high part being worn down heavily and the low part lightly. In the case of the viscous substance hindering means, as has been seen, the low part of the commutator is not touched at all till the high part has been worn down completely. How friction can be used to true up a commutator can be seen from the fact that the net force causing the advancement of the abrasive is only the excess of the spring or weight over the friction hindering means. On the other hand the total force necessary to cause a retrograde movement of the abrasive is equal to the sum of the friction and the force of the spring or weight. Consequently the reaction pressure of the commutator on the abrasive will be much greater when the abrasive is being shoved backward from the commutator than when the abrasive is merely stopped in its advancement towards the commutator. After the high level part of the commutator comes un-

der the abrasive and the abrasive necessarily ceases any further retrograde movement, the slight spring in the apparatus and its supports as a whole may be made to cause the abrasive to continue to exert the maximum pressure on the level high part of the commutator. Consequently, since the abrasive exerts a heavy pressure on the high part of the commutator and a light pressure on the low part of the commutator, the commutator will finally become true.

In forms of the invention described in this application, I employ in my improved truing means a tilting, rocking or canting member which cooperates with the brush or brush-holder to resist or prevent movement of the brush.

Numerous objects and advantages of my invention other than those above noted will appear from the following description taken in connection with the accompanying drawings wherein:

Figure 34 is a view similar to Figure 32 but showing a still further modification.

35 Figures 1, 2, 3 and 4 show how an attachment may be added to a standard type of brush holder to convert the latter, without mutilation, into either a positive feed brush holder or into a brush holder with a hindered motion pressure finger, either type being 40 changed into the other by a simple screw adjustment.

45 Referring to Figures 1, 2, 3, and 4, the U-shaped standard or guide 1 is secured by the pigtail retaining screw 2 through a hole in the horizontal cross-bar of the said U-shaped member 1, to the lug 64 of the brush holder 4. Slidably mounted on said vertical U-shaped guide 1 is the two-part, L-shaped, brush-advancing arm 5, engagement of the horizontal bar 6 of said arm being made by the cross-head 7 at the end of said horizontal bar. The sides of the cross-head are made up of the right angle and enlarged ends 8 of the horizontal bar 6, and the L-shaped brackets 9 riveted to said horizontal bar 6. In the enlarged ends 8 are slots 11 in which are mounted the small screws 12 and 13 vertically adjustable in said slots 11. The twin halves of the arm 5 are connected by the screw 22, on 50 which is the tube 23; the thrust of the brush-

holder pressure finger 24 is received by this screw and tube, said screw being threaded into one of several holes 25 to vary the leverage of the pressure finger on the horizontal bar 6, thus varying the friction of the cross-head 7 on the vertical guide, and, consequently, the force with which the brush is brought into contact with a flat spot in the commutator. The holes 25a are of body size and are unthreaded.

55 The friction of the cross-head, that is, the effect of the binding engagement between the cross-head and the guide in resisting motion in one direction or the other on the guide, may be varied by varying its effective length, the effective length depending on the position of the screws 12 and 13 in the slot 11. In varying the position of the screws 12 and 13 to vary the effective length of the cross-head 7, in order to vary the friction, the position of the upper screw 12 has an effect when the arm 5 is canted clockwise; and the position of the lower screw 13 has an effect when the arm is canted counter-clockwise. In a clockwise cant, corner 33 and the head of screw 12 are the friction, or bearing points, the vertical distance between them being the effective length of the cross-head 7. In a counter-clockwise cant, corner 54 and the head of screw 13 are the friction, or bearing points.

60 It is obvious that if only one force, such as the reactive thrust of the brush 35, acts upwards on the arm 5, the cant will be counter-clockwise. It is obvious also that if only one force, such as the pressure finger 24, acts downwards on the arm 5, the cant will be clockwise. If, however, both the pressure finger and the brush act on the arm 5 at the same time, the cant is reversed, being now counter-clockwise instead of clockwise as in the case just mentioned. Consequently, if we wish to vary the friction of the cross-head 7 when the arm 5 is in engagement with the brush 35, screw 13 should be adjusted in the slot 11, keeping it, however, below the level of the corner 54. If it is desired to lock the arm 5 on the upper part of the guide 1 to get the arm 5 out of the way of the brush-holder box 36 in order to insert a new brush or abrasive member, the friction on the cross-head may be increased by lowering screw 12, keeping it, however, above the level of the corner 33.

65 Between the extremities of the limbs of the U-shaped guide 1 is mounted a pair of concentric cylinders 41 and 42 with a coating of asphalt 43 between them; the inner one 42 slightly the longer, fitting accurately but freely between said extremities, is clamped thereto by the screw 44. To the outer cylinder is clamped by the screw 45 the lever 46 swivelly connected by the pin 47 to the connecting rod 48, the latter being swivelly connected by the pin 49 to the brush-advancing 70 75 80 85 90 95 100 105 110 115 120 125 130

5 arm 5. Riveted to the feet 50 of the brush-advancing arm 5 are the thin phosphor bronze spring 50a and cross-bar 50b, a shoe 50c being riveted to the spring 50a. The thumb-screw 51, threaded into the cross-bar 50b and secured by the thumb-nut 52, may be adjusted to limit or annul the action of the spring 50a.

10 The pigtail retaining screw 2 is set up against a stiff lock washer 56, but not quite to the limit. Under an excessive reaction thrust of the brush 35, the lock washer can be compressed slightly, thus permitting the U-shaped guide 1 to be tilted slightly to 15 the left, thus giving relief to the excessive reaction thrust.

10 The sides and top of the brush or active member 35 may be smeared with a coating of some sticky or pasty substance 59, such as 20 cylinder oil and graphite mixed to a pasty consistency. This has a tendency to stop the chatter of the active member when a pure abrasive, and when the commutator is running against the acute angle of the abrasive.

25 This pasty filler 59 may delay the movement of the brush or abrasive; consequently the asphalt 43 may in certain cases be omitted or thrown out of action, and yet we can get delayed action from the pasty filler alone.

30 In the operation of this brush holder the asphalt hindering means may be thrown out of action by backing off slightly screw 44; or screw 45 may be backed off, or one of the pins 47 or 49 removed.

35 To advance the active member positively, screw 13 is raised till the effective length of the cross-head becomes so short that the reactive thrust of the brush cramps the cross-head on the guide 1 and prevents the cross-head from sliding upwards on the guide 1.

40 How hard the brush or abrasive member is brought into contact with the low spot of the commutator depends on the position of the screw 22 in one of the holes 25a; with the 45 screw 22 in the left hole, as shown in the drawings, the contact pressure is least; with screw 22 in the right hole the contact pressure is greatest.

45 When it is desired to operate non-positively the screw 13 is lowered till the reactive thrust of the brush or active member will not cramp or lock the cross-head on the guide 1.

50 To avoid any possibility of the cross-head cramping and stopping on a downward movement, the screw 12 may be kept in its highest position; although there is small possibility of this happening if the brush-advancing arm 5 is in contact with the brush or abrasive member at the start of operations.

55 Where there is no abrupt jump from the low to the high part of the commutator, the delayed action hindering means may be omitted; when, however, there is an abrupt 60 jump it is generally preferable to use some

form of delayed action hindering means, such as the asphalt hindering means.

65 Where the low part of the commutator is not very deep, or within the limits of the inherent structural yielding of the device, a positive feed may be used; in this way we can get a heavy pressure on the high parts of the commutator and a rapid cutting down of the same. Where the flat spot of the commutator is deep or greater than the inherent structural yielding of the device the positive feed may be omitted; however, relief means in the form of the stiff lock washer 56 is provided so that a positive feed may be used even where the low spot is deep. But a positive feed with delaying means may be used to true a deep flat spot without relief means.

70 Relief means are also provided by a retro-grade movement of the box itself, independent of the rest of the brush-holder body. A dovetail tongue 61 in the shank 3 engages a complementary dovetail groove 62 in the rear wall of the box 36. A lug 64 integral with box 36 supports the feeding attachment, and is strongly held against shank 3 by spring 65 stressed by cap-screw 66 threaded into shank 3, said spring being compressed under an excessive brush thrust.

75 The purpose of the phosphor bronze spring 50a is to give a quick follow up to the brush independent of the movement of the other parts of the apparatus, as in the case of high speed machines with slight irregularities in the commutator. The screw 51 may be adjusted to limit the rebound of the brush in this case to any amount desired. Where an abrasive brush is being advanced under the control of delayed action hindering means and it is desired not to lose the current carrying capacity of even one brush (as where 80 there are only two or four or a few brushes on a commutator) this phosphor bronze spring will serve to keep the brush in contact with the low spots of the commutator as well as the high parts. Where it is desired to hurdle the flat spots of the commutator the thumb-screw 51 is advanced till it makes contact with the spring 50a in its unsprung position. The spring 50a is preferably comparatively weak—that is, in comparison with the 85 spring actuating the brush-holder pressure finger 24.

90 It is evident from the above explanation that by a simple adjustment of screws a brush holder of a common type may be converted into a positive feed brush holder with only a nominal amount of friction to hinder the advancement of the brush or abrasive into the flat spot of the commutator; or this friction, instead of being nominal, may be regulated to be of substantial amount; or the movement may be hindered by delaying means, such as a viscous substance like asphalt or other sluggishly yielding substance. The asphalt can be easily made to hinder in the forward 95

direction only, as by the simple substitution of a stranded wire or chain for the connecting rod 48.

Or the effective length of the cross-head 5 may be adjusted to avoid the positive feed; in this case we may have friction hindering means with or without asphalt hindering means. Both the friction to hinder a forward movement and to hinder a retrograde 10 movement are independently adjustable. The asphalt hindering means may be used alone, the friction being regulated to be merely nominal.

Instead of a pasty filler made up of cylinder oil and graphite, various other powdery substances may be used to mix with the cylinder oil; some of these are whiting, powdered chalk, clay, carbon powder. Instead of cylinder oil, other oils or greases may be used 20 to mix with the solid substances; some of these are vaseline, glycerine and castor oil. Other substances in their commercial form are adapted to act as a filler between the brush or abrasive and the brush-holder box 25 and cause a sluggish movement of the brush or abrasive; the solid belt dressing in common use is one of these; another is modeling clay. This modeling clay is made up of clay and glycerine; more glycerine may be added to 30 make it less doughy and more pasty. Cylinder oil may be mixed with asphalt to reduce its viscosity to any amount desired. The sticky substance used on sticky fly-paper may be used as delayed action hindering means; 35 this is made of resin and castor oil.

Instead of using a pasty filler to prevent chattering of the abrasive member, a form of construction may be given the abrasive member that will tend to stop chattering. Such a 40 form as is described in a copending application Serial Number 278,751 filed May 18, 1929, an abrasive member with a wedge-shaped end coacting with a pusher member with a similar wedge-shaped end, will tend to 45 stop chattering of the abrasive member or abrasive brush.

In the modification shown in Figures 5 and 6 a U-shaped guide 61 is secured by the screw 62 to the brush-holder shank 63. Slidably mounted in this U-shaped guide is the inverted L-shaped, brush-engaging member 64 made up of two similar L-shaped members 65, which are integrally united to form a unit by the contact tip 66 at the lower end 55 of the vertical member, and the rivet 67 and spacing bushing 68 near the middle of the horizontal portion 65 of the L-shaped member 64. The pressure finger 69 exerts its thrust on the spacing bushing 68. The bent ends 70 and the riveted blocks 71 form the sides of a groove to coact with the limbs of the guide 61.

In the operation of this attachment for truing a commutator an abrasive brush 72 65 or abrasive block is substituted for the usual

brush. It is evident that when the member 64 is advancing there can be no binding of this member on the guide 61. When a backward thrust of the brush comes because of a high spot of the commutator coming under 70 the brush the member 64 instantly locks on the guide 61 without any slight retrograde movement while lost motion or backlash is being taken up. It is evident that if the width of the horizontal parts 65 of the L-shaped member is great enough to not lock, 75 then we have a friction finger brush holder instead of a positive feed brush holder.

In the modification shown in Figures 7 and 8 there is formed in the brush-holder body 80 a guide 81 located between the brush-holder box 82 and the brush-holder shank 83. Slidably disposed in this guide is the longer limb 84 of a U-shaped brush-engaging member 85, the shorter limb 86 of which makes contact 85 with the brush 87 at 88. To the end of this longer limb 84 is attached by the rivets 89 a spacing member 89a, the purpose of which is to permit only a portion of the limb 84 to 90 come in contact with the sides of the groove 90 81. The spacing member 89a can be easily removed and a wider or narrower one substituted. The narrower this one is, the greater is the tendency of the limb 84 to bind in the groove 81 when the U-shaped member 95 85 is subjected to an offset thrust, such as is received at 88 from the reaction pressure of the brush 87. The thrust of the brush-holder pressure finger comes at 90 between the limbs 84 and 86, thus advancing the longer limb 84 100 as far as possible in the guide 81 and effectively avoiding any manifestation of backlash or lost motion when a high spot of the commutator comes under the brush 87 and shoves it backwards. What yielding there 105 is in this case will have to come from the structural yielding of the brush holder and its supporting parts—the brush-holder stud and brush-holder yoke.

When it is desired to use the brush holder 110 in the usual way, the U-shaped member is pulled out of the groove without the necessity of removing the screw or nuts or other means of attachment to the brush holder body. If the spacing member 89a is too wide to lock 115 under the reaction thrust of the brush, the result is the equivalent of a friction finger, or rather the equivalent of a friction finger brush-holder.

In the modification shown in Figures 9 120 and 10 a box guide 91, two sides of which are 92 and 93, is attached by the screw 94 to the front wall 95 of the brush-holder box 96. In the inner side 92 of the guide 91 is the hole 97 large enough to permit to project there-through the protuberance 98, threaded for the usual purpose of receiving the brush pigtail retaining screw, for which has been substituted the longer screw 94. The inverted 125 U-shaped brush-engaging member 99 has the 130

side that slidably engages the box guide 91 divided into two parts 100; this division is for the purpose of straddling the screw 94 and protuberance 98. The blocks 101 riveted 5 to the parts 100 determine the binding or pinching limits of the parts 100 in the guide 91.

The vertical width of the block 101 determines whether this type of brush holder is a 10 positive feed brush holder or the equivalent of a friction finger brush holder. It is the former when the blocks are narrow enough to cause locking under the reaction thrust of the brush; and the latter when the blocks 15 are too wide to cause locking.

In the modification shown in Figures 11 and 12 there is a circumferentially grooved or collared bushing 102 secured to the front side of the brush-holder box 103 by the cap- 20 screw 104 substituted for the brush-holder pigtail retaining screw. To brace the structure there is provided the flat strap 105 and the thumb-screw 106. All spring or yielding is taken up by snugly setting up the thumb- 25 screw 106, which is then secured by the knurled jam-nut 107. The brush-engaging U-shaped member 108 has the longer side divided into two limbs 109, 109 which are mounted astride the bushing 102 and in the 30 groove 110 thereof. The said brush-engaging member 108 is forwardly actuated by the springs 110a and screws 110b, the springs 110a being put under tension by the knurled thumb-nuts 110c. The positive advancement 35 of the member arises from the fact that the reaction offset thrust of the brush 110d is so far to the side of the limbs 109, 109 that they bind or pinch in the groove 110 when the member 108 is shoved backwards by the brush. 40 There is no locking of the member 108 when moving forward, because the screw 110b is not offset far enough from the limbs to cause the latter to lock in the groove 110.

It is evident that by changing the proportion 45 of the parts, such as by decreasing the distance between the sides of the U-shaped member or by increasing the diameter of the groove, we can get the equivalent of a friction finger brush holder.

50 In the modification shown in Figure 13 the pressure finger 121 is slidably mounted on the stud 122, the right-hand end of said pressure finger being expanded into a cylindrical cross-head 123 which slides freely on the said stud. The reduced end 124 of this stud, together with the nut 125, serve to close 55 the clamp 126 which clamps the brush-holder shank 127 to the brush-holder stud 128. Riveted to the reduced upper end of the stud 60 122 is the spring holder 129 housing the flat spring 130, the outer end 131 of which makes contact with the pressure finger 121 in the shallow trough 132 on the top side of said pressure finger. The disposal of the end of 65 the spring 130 in the trough of the pressure

finger serves to keep the said pressure finger in alignment with the axis of the brush-holder box 123. Additional security as to alignment may be had by means of the keyway 134 in the stud 122, into which keyway projects the end of the screw 135 held securely in the cross-head 123 by the jam-nut 134. For the purpose of regulating or annuling the action of the auxiliary spring 137 there is mounted in the outer end of the pressure finger 121 the screw 138 secured by the knurled thumb-nut 139. This screw 139 is in line with the center of the brush-engaging hammer 140 riveted to the end of the auxiliary spring 137. The set-screw 141 serves to keep the stud 122 in position when the nut 125 is backed off. 70 75 80

When the pressure finger 121 is resisting an upward thrust of the brush 142 the cross-head 123 makes contact with the stud 122 at the points *a* and *b*. Through these points are drawn the construction line *ao* and *bo*, making an angle ϕ with a normal to the stud 122, the angle ϕ being the angle whose tangent is equal to the coefficient of friction. This angle is taken as 15 degrees corresponding to a coefficient of friction of something less than 27/100. If the reaction thrust of the brush is to the left of a vertical line through the point of intersection *o* there will be no slipping of the pressure finger on the stud 122; if the reaction thrust of the brush is to the right of the point *o* the pressure finger will slip on the stud, but with frictional resistance. With the former construction we have a positive feed brush holder; in the latter construction a friction finger brush holder. The point of contact *c* of the spring 139 with the pressure finger should preferably be to the right of the point *o*. Near the top of the stud 122 is the groove 143 adapted to receive the end of the screw 135, thereby permitting swiveling of the pressure finger 121 on the stud 142 when the pressure finger is raised to its maximum position. In this way a new brush can be inserted in the brush-holder box 135. 90 95 100 105 110

When this brush holder is used in the usual way the screw 138 is backed off widely or removed, thus permitting unimpeded play to the auxiliary spring 137. If the brush holder is used with high-speed electric machines to prevent the rebound of the brush from commutators with slight flat spots in them the desired tension is first put on the main spring 130 by adjustment of the arm 144 in the notches 145. The screw 138 is then advanced to contact or nearly to contact with the brush-engaging hammer 140. When the brush holder is used to true up a commutator, an abrasive brush or an abrasive block is substituted for the usual brush; then, with a slight stress on the auxiliary spring 139 the screw 138 is advanced to contact with the brush-engaging hammer 140; finally the proper 115 120 125 130

stress is put on the main spring 130. To permit a slight retrograde movement of the brush when a high spot of the commutator comes under the brush, dependence is made on a slight structural yielding of the various parts—the pressure finger, the stud 122, the clamps 126, the brush-holder stud 128 and the brush-holder yoke.

In Figures 14, 15, 16 and 17 is shown a brush holder substantially of a form now in use, and the means added to adapt it to advance the brush positively. The brush-holder shank is in the form of a vertical stem 191 integral with the brush-holder box 192 at its lower end. By means of the clamping members 193 and the square-headed bolts 194 vertically adjustable in the slot 195 in the stem 191 the brush holder is secured to the brush-holder stud 196. A U-shaped wedge-shaped sheet metal catch 197 serves to adjust the tension of the brush-actuating spring 198. The catch holds its position through the engagement of the edge 199 of the horizontal part of the catch with the teeth 200 of the stem, and the engagement of the nibs 201 in its lower part with the ribs 202 of the stem 191. The lower end of the spring 198 is secured to the rod 203, the lower end 204 of which rod engages the brush 205 in the hole 206; in this way the alignment of the spring is preserved.

The added part that adapts this old type of brush holder for positive feeding is the friction or chocking cap 207, shown separately in the two perspective views in Figures 16 and 17. This friction cap 207 is intended to slide on the stem 191 and for this purpose has projecting from the main part two L-shaped lugs 208 the free limbs of which slidably engage the grooves 209 in the stem 191, the sides 210 and 210a of the limbs of the L-shaped lugs making contact with the sides of the groove 209. If there is friction or binding by the lugs against the sides of the grooves when the cap 207 is moving downwards under the action of the spring 198 the pressure comes on the lines "a" and "b". The vertical distance between "a" and "b" is preferably made so great that the friction will not be great enough to stop the forward motion of the cap 207. On a retrograde movement of the cap 207 under the reaction thrust of the brush 205, the pressure on the lugs 208 comes at the lines "c" and "d." The vertical distance between "c" and "d" is so small that the lugs bind in the groove when the cap receives a reaction thrust of the brush at the point 211. Since the thrust of the spring 198 is received at a point 211a on the cap between its point of engagement 211 with the brush and its contact point with the groove 209 there is no backlash to be taken up and prevent instant chocking of the cap under the reaction thrust of the brush as a high spot of the commutator 212 comes under

the brush. A cotter pin 213 in the groove at the upper end of the stem serves to keep the parts assembled.

In truing a commutator by this type of positive feed brush an abrasive brush or abrasive member is substituted for the usual brush. By taking out the cotter pin 213 and removing the cap 207 the brush holder will act non-positively like the usual brush holder. Where another type of brush holder is in use a few of this type of brush holder may be substituted for or added to the other brush holders. In this case an abrasive member will have to be used instead of an abrasive brush; and the brush holder should preferably be insulated from the brush holder stud, as by making the clamping blocks 193 of fibre or by using a fibre bushing on the brush-holder stud 196.

In Figure 18 is shown how a brush holder of a type in common use has been modified to adapt it to positive feeding. The ordinary brush-holder finger is removed, and a spiral spring 215 with a longer arm 216 substituted for the usual spring. A short vertical tube 217 is secured to the brush-holder shank 218 by the cap-screw 219. On this vertical tube is splined the pressure finger 220, the expanded tubular end 221 of said pressure finger engaging the vertical tube 217 and key 222, which key restrains the pressure finger to a vertical movement till the extreme upward position of the pressure finger has been reached, when it passes out of engagement with the key 222 and is then free to swivel on the vertical tube 217 to permit the easy insertion of a brush.

Figure 19 shows the means of adapting one of the earlier types of brush holders to positive feeding. In this type of brush holder the spring 241 is slotted from about the point 242 to the end of the spring. Positioned in this slot is the square rod 243 rigidly attached to the brush-holder shank 244 by the clamp 245 and screws 246. Slidably mounted on the square rod 243 by means of the square hole 247 near its end is the brush-engaging horizontal bar 248 making contact near its outer end with the brush or abrasive member 249 bearing on the commutator 250. The spring 241 acts on the bar 248 through the spacing block 251 adjustably secured by the screw 252 in one of several holes 253.

In the modification shown in Figure 20 one of the edges 268 of the brush 269 is reduced slightly in step fashion at the upper end to furnish room and leverage for receiving the vertical leg 270 of the inverted L-shaped bracket 271, the horizontal leg 272 of said bracket being in a position to receive the thrust of the pressure finger 272, part of said thrust being transmitted axially to the brush and a part laterally to the walls of the brush-holder box. By cutting away the step 273a a bit, friction will be increased on account

of the greater leverage thus given to the bracket 271; on the other hand, friction will be reduced if the step 274 is cut away a bit, because the leverage in this case will not be so great.

In the modification shown in Figure 21 the upper part of one of the edges of the brush is reduced slightly in step fashion as is the brush in Figure 20. Formed integral with the rest 275 and extending laterally therefrom is the rectangular Z-shaped strap 276 ending in a nib 277 which loosely enters a small, square hole 278 in the vertical leg 279 of the inverted L-shaped bracket 280, the end 15 of the nib 277 being peened over in order to secure the bracket 280 in loosely swivelling assemblage with the brush 281.

In Figures 22, 23 and 24 is shown another modification of the positive feed brush holder which differs from most forms previously described in respect to relief means for permitting a retrograde movement of the brush when a certain maximum pressure has been exceeded. In certain of the positive feed 20 brush holders previously described the relief spring permitted a retrograde movement to the brush when a certain pressure has been exceeded, but not to the brush holder; in this modification both the brush and the brush holder move backwards when a certain pressure is exceeded, thus doing away with the possibility of wear of the brush and the brush holder.

In the brush holder shown in Figures 22, 23 and 24 the hexagonal brush-holder stud 301 is secured to the machine frame in a certain definite position in relation to the hexagonal faces of the stud. Fitting on said stud and insulated from it by a hexagonal fibre tube, 40 is the thick metal sleeve 302 secured to said hexagonal stud by the cap-screw 303 and jam-nut 304. To the thick sleeve 302 is slidingly secured by the cap-screws 305 and the flat bar 306 the brush-holder set 307, consisting of four brush holders integrally united to themselves and to the tongue 308.

In the shank 309 of each brush holder is formed a narrow compartment or groove 310 with its side walls on both sides partly cut away in the middle part to permit passage of the brush-holder pressure finger 311. Mounted in this groove by its step-like expanded end 312 is the brush-engaging square rod or auxiliary pressure finger 313 forwardly actuated to advance the brush by the pressure finger spring 311 which also serves as a pressure finger, the pressure finger being merely the free end of the flat spring 311.

In the tongue 308 are elongated holes 313a by which vertical adjustment is made to fit commutators of different diameters when the brush holder is used in the usual way without the truing device. When the truing attachment is used and where there may be 60 more retrograde movement of the brush or

abrasive (if an abrasive block has been substituted for the brush) than can be taken care of by the mere structural yielding of the brush holder and supporting parts, provision is made for a vertical relief movement 70 of the tongue 308 by not setting up the cap-screws 305 quite tight; or by setting them up against a collar or spacing member that will allow a slight clearance between the tongue and the flat face of the thick sleeve 302. For 75 advancing the brush holder towards the commutator there are straps 314 bearing against the top of the tongue 308, the stiff flat spring 317 to advance the said straps 314 and jam-nuts 315 on the studs 316 to stress the spring 80 85 90 95 100 105 110 115 120 125 130 135 140 145 150 155 160 165 170 175 180 185 190 195 200 205 210 215 220 225 230 235 240 245 250 255 260 265 270 275 280 285 result of the slight to-and-fro movement of the brush holder in the box. It is evident that with a positive feed attachment in use that this to-and-fro movement is eliminated, 5 all retrograde movements of the brush being accompanied by an equal retrograde movement of the brush holder as well. Consequently the wear of the brush and box due to the sand and grit is eliminated. It is evident that the groove 310 may be adjacent to 10 the brush-holder box, in which case they will have a common wall.

In modifications shown in Figures 25 to 15 28 the movement of the brush-holder box and its integral or accessory parts is due to the brush-holder box and integral parts forming one of the movable sides of a parallelogram-of-motion arrangement, the other two movable sides being two pairs of comparatively flat springs, which are stiff in comparison 20 with the actuating spring of the brush-holder pressure finger.

On the square brush-holder stud 355 with 25 a fibre tube telescoping and insulating it there is secured the square metal sleeve 356 to which are attached the fixed ends of the four flat springs 357, the other ends of said springs being attached to the movable guide 358 to which is adjustably secured by the cap-bolts 359 the tongue 360 integral with the brush-holder box 361. It is evident that when a certain maximum brush pressure has 30 been exceeded the said springs 357 will bend and allow a retrograde movement of the brush holder box 361. For the purpose of 35 truing commutators most efficiently in combination with a positive feed attachment, it is desirable that these springs 357 be assembled in such a way that they have a strong downward stress. Such a downward stress 40 may be secured by giving the springs before assemblage an initial flexure as shown in Figures 27 and 28 for the upper and lower springs respectively. By properly choosing the springs the relief movement of the brush holder will take place before it is damaged or before any shearing action of the commutator on the brush or abrasive occurs. It 45 is evident that instead of springs connecting links and pivots could be used to get a motion of the brush holder parallel to its initial position. The reason for having four springs instead of two is to diminish the effect that the breaking of one spring will have 50 on the functioning of the brush holder.

Referring to Figures 29 and 30, on the rounded-cornered square brush-holder stud 371 telescoped and insulated by a fibre tube, is mounted the thick sleeve 372 turned down at either end to form a spindle 373, on which 55 swivels, by means of the split bearing clamp 374-374a, the guide 375 in which is mounted adjustable by the cap-bolts 376, the tongue 376a integrally united to the brush-holder boxes 377. To give a constant thrust of the 60 brush-holder towards the commutator there

is the stiff spiral spring 378 stressed between the lug 379 projecting from the clamp 374a and the square bar 380 attached to the sleeve 372. By means of the nut 381 on the cap-bolt 382 any desired stress can be secured on 70 spring 378. The forward motion of the brush holder is stopped by the clamp 374 coming in contact with the ends of the square bar 380. Clamps 374a and guide 375 are integral.

One objection to the swivel type of relief 75 means is that a retrograde movement of the brush holder tends to tip the brush slightly on the commutator.

Referring to Figure 31, to the shank 391 of the brush holder 392 is clamped by the clamp 393 and screws 394 the vertical snubber bar 395 of rectangular section and notched on the right-hand face with teeth 396 like those in a fine file, the formation of the teeth being such that a downward motion of the snubber bar (if it were used as a file) would correspond to the cutting stroke of the ordinary fine file. On the snubber bar 395 is slidably mounted the auxiliary pressure finger 397. By cutting away one side of the square hole in the auxiliary pressure finger 397, as indicated by the dotted line 398, a chisel edge 399 is secured in the auxiliary pressure finger to engage the teeth 396. If there are fifty teeth to the inch it is evident that the greatest retrograde 95 movement of the brush or abrasive can amount to no more than 2/100 of an inch; and the average retrograde movement is of course much less than this. The teeth may be formed in a separate piece like a nail file and 100 attached to the snubber bar by screws; or the teeth may be cut in soft steel snubber bar, which is then case-hardened, the tooth-engaging part of the auxiliary pressure finger being preferably also case-hardened. It is evident that without any teeth on the snubber bar 398, said snubber bar being left soft and the engaging edge 399 of the auxiliary pressure finger case-hardened, the hardened edge 399 will tend to dig into the snubber bar and 105 prevent any retrograde movement of the brush or abrasive.

It is evident also that the variation of hardened teeth in the snubber bar in engagement with a soft auxiliary pressure finger 115 will be likewise operative.

In the modification shown in Figures 32 and 33 a brush holder of a type in common use is adapted for truing a commutator by the addition of a simple friction element and without any mutilation of the brush holder structure. The two vertical rods 421 fixed in the foot plate 422 are mounted on the top of the brush-holder shank 423, the screw 424 that secures the terminal of the brush-holder 120 pigtail 425 being used to secure the foot plate 125 to the brush-holder shank.

Slidably mounted on the vertical rods 421, 421 is a pair of blocks 426 from which project to the right and downwards a pair of 130

limbs 427, 427, terminating in a common uniting foot or contact tip 428. The brush-holder pressure finger 429 makes contact with this contact tip at the point 430. The spring 5 431 removably attached by the screw 432 to the contact tip, has the same function as a pressure finger auxiliary spring. In the lower parts of the blocks 426 are several holes 432a, 432a threaded to receive the screws 10 433, 433, these screws being of a length to project slightly within the bore of the block 426, 426 when the screw 433, 433 is set up tightly. The purpose of this screw is to vary the effective cramping or binding or 15 pinching length of the blocks 426, 426. The reaction upward thrust of the brush 434, will tend to rotate the blocks 426, 426. The binding points of the blocks 426, 426 on the rods 421, 421 will be at the top front parts of the 20 blocks and at the bottom rear parts of the blocks. The binding or cramping or pinching length of the blocks in this case will be the vertical thickness of the blocks. If the screw 433 is in position the lower binding 25 point will come on the screw 433, so that the effective binding length of the block is not the vertical length but only the length from the top of the block to the point of the screw 433. Consequently the higher the hole in 30 which is threaded the screw 433 the greater the friction of the blocks on the rods 421, 421. The collar 434 secured by the screw 435 on the rod 421 limits the advancement of the blocks 426, 426.

35 When this attachment is used for truing purposes it is preferable that the spring 431 be removed altogether, or that such a thin spring be used that its resiliency is negligible or small in comparison with that of the pressure finger actuating spring 436. For the usual brush an abrasive brush or an abrasive block is preferably submitted when a commutator is to be trued up.

Joining the limbs 427, 427 is the pin 437 45 secured by the screw 438. The thrust of the pressure finger may be exerted on this pin instead of on the contact tip 428 at the point 430.

As said before, the pinching or binding 50 points of the blocks 426, 426 on an upward thrust will be the front upper corner and lower rear corner. It is evident that the vertical distance between two diagonal corners may be changed, and by this means we can 55 get the desired binding effect on the upward thrust; or vary the friction of the upward or downward thrust. This is what is in reality done by the different positions of the screws 433.

60 In Figure 34 the truing attachment is shown applied to a brush holder in which the pigtail is fastened to the front of the brush-holder box instead of to the brush-holder shank, as is the case in the modification shown 65 in Figures 32 and 33.

On the front face of the brush-holder box 451 is mounted by means of the screws 452 and 453 the vertical rod 454. Slidably mounted on the rod 454 is the inverted L-shaped bracket 455, the vertical downwardly-extending limb 456 being in line with the axis of the brush-holder box 451. This vertical limb 456 may be replaced by a tube up to the line 456a. The vertical limb 456 of the bracket is tubular, and slidably mounted therein is the rod 458 bearing at its lower end the shoe or contact tip 459. A spring 460 interposed between the contact tip 459 and the end of the vertical limb 456 serves the same purpose as the auxiliary spring on the ordinary brush holder. By adjustment of the nuts 461 the initial stiffness of the spring can be regulated. Or the spring 460 can be thrown out of action altogether by tightening the nuts 461 till the spring 460 is completely compressed. The tip of the screw 462 projecting slightly into the keyway 463 serves to spline the limb 464 of the bracket 455 on the rod 454. The bracket 455 is actuated by the spring 465. One end of the spring 465 is attached to the bracket 455 by means of the screw 466. The other end of the spring 465 is attached to the U-shaped clamping member 467 which is vertically adjustable by means of the thumb-screw 468. To prevent the spring 465 and rod 454 from being burned or pitted by a possible flash-over, a guard 469 in the form of a strip of metal or leatheroid paper is placed in front of the said spring and rod. The lower edge of this strip or guard is apertured to receive the screw 458, to which it is secured by the milled nuts 470. From the point *a* to the point *b* the strip or guard 469 is slotted along a middle line, the slot being wide enough to receive the bodies of the thumb-screws 462, 468. By this means the bracket 455 and the clamp 467 can move along the rod 454 without interference from the guard 469. 100

In the operation of this modification an abrasive brush 471 or an abrasive block is preferably substituted for the usual brush. The spring 460 is then entirely compressed, or compressed till it is under considerable stress, by adjustment of the nuts 461. The spring 465 is then put under stress by moving the clamp 467 down the rod 454. 105

The truing action of this modification is due to the fact that much less pressure is required by the flat spot on the commutator to stop the advancement of the brush than is required by the high part of the commutator to force the brush backwards. The ratio of these two pressures will measure in a general way the truing action of the device. To find out what this ratio is, suppose that the vertical width of the bracket limb is $1/2$ inch, that the distance from the center line of the rod 454 to the center line of the vertical limb 456 is 1 inch, and that the coefficient of friction 110

115

120

125

130

is 1/5. Under these assumptions the ratio of the pressure exerted by the high part of the commutator to force the brush backwards to the pressure exerted by the commutator to stop the advancement of the brush is about 9. 5 By decreasing the vertical width of the bracket limb 464 from 1/2 inch to 2/5 inch or less, the bracket limb 464 locks on the rod 454 when the high spot of the commutator forces the brush backwards; that is the bracket, or pressure finger 455 advances positively. 10

Instead of the upper end of the spring 465 being attached to the bracket limb 464 at the 15 point indicated in the Figure 34, it might have been attached at some other point of the bracket limb 464, say midway between the rod 454 and the vertical bracket limb 456, the spring retaining screw 466 being 20 threaded into the middle hole 472. Assuming that the spring 465 still continues to exert a vertical pull, the reaction pressure of the brush necessary to stop the forward motion of the pressure finger or bracket 455 will 25 be about 7/9 of the pressure exerted by the spring 465 while the pressure necessary to force the pressure finger or bracket 455 backwards will be about 3 times the pressure exerted by the spring 465. The ratio of the 30 two pressures will be 27/7, or nearly 4. These figures would substantially apply to the modification shown in Figures 32 and 33. If the pressure finger 429 makes contact with the vertically sliding member on the pin 437 35 instead of on the shoe 428 at the point 430 then this ratio will be considerably greater than 4. From these figures it is clear that the abrasive brush in Figures 32, 33 and 34 acts most efficiently to true up a commutator 40 when the actuating member makes contact with the sliding member near the axis of the sliding member.

It will be noted that in the modifications shown in Figures 32, 33, and 34 there can be 45 no binding or locking to prevent the forward motion of the sliding members.

When my improved brush holder is used with an abrasive brush for truing commutators the brush employed should contain 50 enough abrasive to produce a truing effect sufficient to more than offset the tendency of sparking between the brush and commutator to cause the commutator to become out of round. The abrasive content may range 55 from 10% to 70% although in certain cases I may employ less than 10%. I find that a brush containing 25% abrasive and 75% carbon or similar conducting material produces 60 very satisfactory results. By abrasive I mean a material which has a substantial abrasive effect on the metal of the commutator bars, such as carborundum, corundum or emery as disclosed in my application Ser. 65 No. 278,749, of even date herewith.

Other forms of the generic invention herein disclosed are described in my co-pending applications Ser. Nos. 278,748 to 278,751, all of even date herewith, and my Patent #1,727,112, granted Sept. 3, 1929. Said patent and applications Ser. Nos. 278,749 and 278,750, contain claims broadly to the idea of causing the brush to exert greater pressure on the high parts of the commutator than on low parts, particularly for the purpose of truing the commutator. 70 75

I claim:

1. In a dynamo electric machine having a commutator, a brush and a stationary brush-holder support, the combination of a brush holder comprising means for directing the advancement of the brush toward the commutator, means for attaching the brush directing means to said support, actuating means for advancing the brush toward the 80 commutator, a stationary guide, an intermediate member slidably mounted on said guide, said intermediate member receiving the thrust of the actuating member and transmitting it to the brush, the line of thrust of the actuating member being substantially offset from the reaction line of thrust of the brush, so as to cause a binding engagement between said intermediate member and 85 guide. 90 95

2. In a dynamo electric machine having a commutator, a brush, a stationary brush-holder support, the combination of a brush holder comprising means for directing the advancement of the brush toward the commutator, means for attaching the brush directing means to said support, actuating means for advancing the brush toward the commutator, a stationary guide, an intermediate member slidably mounted on said guide, said intermediate member receiving the thrust of the actuating member and transmitting it to the brush, the line of thrust of the actuating member being substantially offset from the reaction line of thrust of the brush, so as to cause a binding engagement between said intermediate member and guide, 100 105 110

and means for varying the intermediate member's effective length engaging the stationary guide. 115

3. In a dynamo electric machine having a commutator, a brush, a stationary brush-holder support, the combination of a brush holder comprising means for directing the advancement of the brush toward the commutator, means for attaching the brush directing means to said support, actuating means for advancing the brush toward the commutator, a stationary guide, an intermediate member slidably mounted on said guide, said intermediate member receiving the thrust of the actuating member and transmitting it to the brush, the line of thrust of the actuating member being substantially offset from the reaction line of 120 125 130

thrust of the brush so as to cause a binding engagement between said intermediate member and guide, and means for varying the line of thrust of the actuating means on the 5 intermediate member.

4. In a dynamo electric machine having a commutator, a brush and a stationary brush-holder support, the combination of a brush holder comprising means for directing the 10 advancement of the brush toward the commutator, means for attaching the brush directing means to said support, actuating means for advancing the brush toward the commutator, a guide, an intermediate member 15 in slidable engagement with said guide to receive the thrust of the actuating means and transmit it to the brush, the direction of the reaction line of thrust of the brush passing outside a line joining the guide engaging 20 end of the intermediate member and the point of contact of the actuating means with the intermediate member.

5. In a dynamo electric machine having a commutator, a brush and a stationary brush-holder support, the combination of a brush holder comprising means for directing advancement of the brush toward the commutator, means for attaching said brush directing means to said support, means for advancing the brush toward the commutator, a guide, an intermediate member in slidable engagement with said guide and adapted to receive a lineal thrust of the actuating means for transmission to said brush and adapted 35 to receive the lineal reaction thrust of said brush, the line of one of said thrusts being offset from the axis of the guide sufficiently to cause the intermediate member to exert a substantial canting pressure on said guide.

- 40 6. In a dynamo electric machine having a commutator, a brush and a brush-holder supporting means, the combination with a brush holder secured to said support and comprising a brush guide, means for advancing the brush positively relatively to the brush guide, means permitting a retrograde movement of said guide with said brush, and delayed action hindering means for hindering the movement of said brush.

- 50 7. In a dynamo electric machine having a commutator, a brush and a brush-holder supporting means, the combination of a brush holder secured to said supporting means and comprising a brush guide, means 55 for advancing the brush positively relative to said guide, means permitting retrograde movement of said guide with said brush and slowly deformable means for hindering the movement of the brush.

- 60 8. In a dynamo electric machine having a commutator, a brush and a brush-holder support, the combination of a brush holder secured to said support, and comprising means for directing the advancement of the 65 brush toward the commutator, means for

exerting on said brush a brush advancing thrust and for receiving the reaction thrust of said brush, friction means comprising a guide and a cooperative element slidable along said guide and adapted for tilting engagement therewith at opposed points, said cooperating element being adapted to receive at least one of said thrusts at such an angle and so offset from the axis of the guide as to cause a binding or pinching engagement of said element and guide whereby substantial frictional resistance is offered to the movement of said brush in said brush directing means.

70 9. In a dynamo electric machine having a commutator and a brush-holder support, the combination with a brush holder secured to said support and comprising a brush box, a member movable in said box and formed of material having a greater abrasive effect 75 on said commutator than a consolidated composition of about 90 per cent. brush carbon and 10 per cent. carborundum, means for exerting on said member a thrust to advance said member in said brush box and for receiving the reaction thrust of said member, friction means comprising a guide and a cooperative element slidable along said guide, and adapted for tilting engagement therewith at opposed points, said cooperating element being adapted to receive at least one of said thrusts at such an angle and so offset from the axis of the guide as to cause a binding or pinching engagement of said element, and guide whereby substantial frictional resistance is offered to the movement of said member in said brush box.

80 10. In a dynamo electric machine having a commutator, a brush and a brush-holder support, the combination of a brush holder secured to said support, and comprising means for directing the advancement of the brush toward the commutator, means for exerting on said brush a brush advancing thrust and for receiving the reaction thrust of said brush, friction means comprising a guide and a cooperative element slidable along said guide and adapted for tilting engagement therewith at opposed points, said cooperative element being adapted to receive at least one of said thrusts at such an angle and so offset from the axis of the guide as to cause a binding or pinching engagement of said element, and guide whereby substantial frictional resistance is offered to the retrograde movement of said brush in said brush directing means, and yieldable relief means permitting retrograde movement of said brush when a predetermined reaction thrust is exceeded.

85 11. In a dynamo electric machine having a commutator, a brush and a brush-holder support, the combination of a brush holder secured to said support and comprising means for directing the advancement of the 90 brush toward the commutator, means for

brush toward the commutator, means for exerting on said brush a brush advancing thrust and for receiving the reaction thrust of said brush, friction means comprising a guide and a cooperative element slidable along said guide, and adapted for tilting engagement therewith at opposed points, said cooperating element being adapted to receive at least one of said thrusts at such an angle and so offset from the axis of the guide as to cause a binding or pinching engagement of said element and guide whereby substantial frictional resistance is offered to the retrograde movement of said brush and delayed action means for hindering the advance of the brush.

12. In a dynamo electric machine having a commutator, a brush and a brush-holder support, the combination of a brush holder secured to said support, and comprising means for directing the advancement of the brush toward the commutator, means for exerting on said brush a brush advancing thrust and for receiving the reaction thrust of said brush, friction means comprising a guide and a cooperative element slidable along said guide and adapted for tilting engagement therewith at opposed points, said cooperating element being adapted to receive at least one of said thrusts at such an angle and so offset from the axis of the guide as to cause a binding or pinching engagement of said element and guide whereby substantial frictional resistance is offered to the retrograde movement of said brush, and asphalt hindering means for delaying the advance of said brush.

13. In a dynamo electric machine having a commutator, a brush and a stationary support, the combination of a brush holder comprising a brush guide, means securing said guide to said support and permitting retrograde movement of guide, stressed biasing means resisting said retrograde movement and adapted to yield to permit said retrograde movement only when a predetermined retrograde thrust has been exceeded, means for advancing said brush along said guide, and means locking said brush against retrograde movement relative to said guide.

14. In a dynamo electric machine having a commutator, a brush and a stationary support, the combination of a brush holder comprising a brush guide, means securing said guide to said support and permitting retrograde movement of guide, a stressed spring resisting said retrograde movement and adapted to yield to permit said retrograde movement only when a predetermined retrograde thrust has been exceeded, means for advancing said brush along said guide, and means locking said brush against retrograde movement relative to said guide.

15. In a railway motor having a plurality of brushes arranged side by side, a common

brush holder for said brushes formed with brush guiding means, yieldable means for holding said brush guiding means and permitting an extensive retrograde movement thereof when a predetermined reaction thrust thereon is exceeded, and means for preventing retrograde movement of the brushes in the brush guiding means.

Signed at New York, in the county of New York and State of New York, this 17th day 75 of May, A. D. 1928.

HORACE D. MUNDAY.
